UNITED STATES PATENT OFFICE.

JACQUES KREISLER, OF NEW ROCHELLE, NEW YORK.

DESIGN FOR A BRACELET.

Application filed January 2, 1926. Serial No. 15,931. Term of patent 3½ years.

To all whom it may concern:

Be it known that I, JACQUES KREISLER, a citizen of the United States, residing at New Rochelle, in the county of Westchester and State of New York, have invented a new, original, and ornamental Design for a Bracelet, of which the following is a specification, reference being had to the accompanying drawing, forming a part thereof.

Fig. 2 is an enlarged detailed fragmentary view thereof.

The detailed fragmentary view in the drawing extends throughout the extent of the bracelet.

I claim:

The ornamental design for a bracelet, as shown.

In testimony whereof, I affix my signature.

JACQUES KREISLER.
